UNITED STATES PATENT OFFICE.

BENJAMIN F. HAUGH, OF INDIANAPOLIS, INDIANA.

IMPROVEMENT IN BOLTS FOR PRISON-DOORS.

Specification forming part of Letters Patent No. **81,165**, dated August 18, 1868.

To all whom it may concern:

Be it known that I, BENJAMIN F. HAUGH, of Indianapolis, in the county of Marion and State of Indiana, have invented new and useful Improvements in Iron Prisons; and I do hereby declare that the following is a full, clear, and exact description thereof, reference being had to the accompanying drawings, making part of this specification.

My invention relates to the arrangement of the devices for securing the several doors of the prison within a compartment that is inaccessible from the interior, but which is convenient of access to the jailor or turnkey.

Figure 1 is a ground plan of a prison having but one cell, but showing the arrangement of the several compartments, and also the devices for securing the entrance, corridor, and cell doors, as applicable to a number of cells, whether arranged in stories or on one floor. Fig. 2 is a front elevation of the entrance or exterior doors. Fig. 3 is a transverse section through the compartment F, in which the devices for securing the front and inner doors of the vestibule, and also the lever by which to actuate the vertical bar that secures the corridor-door, are situated. This figure is also a transverse section through the dining-hall and the partition separating it from the corridor and cells, showing the corridor-door and the vertical sliding bar *a* that secures it. Fig. 4 is a section through the vestibule and the front and inner doors thereto, and showing the manner of securing the inner door. Fig. 5 is a front elevation of the cell-doors, showing the device for securing them when they are arranged in two stories. Fig. 6 is a ground plan of a prison having the cells arranged in two stories, and showing more fully the arrangement of a larger and more complete prison, with my improvements applied thereto.

Similar letters of reference indicate corresponding parts in the several figures.

The following description will enable skilled artisans to make and use my invention.

A are the walls of the prison. *B* is the front door; *C*, the vestibule; *D*, the inner door; *E*, the door to compartment *F*.

The locks that secure the inner door *D*, the lever *g*, by which to actuate the device that secures the corridor-door, and also the bolts

and locks that secure the door *E* when shut, are all situated within the compartment *F*, which is made as secure from access from the prison as practicable by making the walls that separate it therefrom solid—that is, having no doors or other openings communicating with the prison or vestibule—thus placing the devices that secure the principal doors out of reach of the prisoners, and, at the same time, in the most convenient and commanding position for the jailor.

The corridor and cell doors are secured by vertical sliding bars *a*, furnished with lugs or catches *e*, that receive the projecting ends of the strap-hinges *d*, which extend across the doors, as shown in Fig. 5.

The vertical bars *a* are coupled by a short toggle-bar, *h*, to a horizontal sliding bar, *G*, that is hung in eyes *i* anchored in the under side of the stone flagging *M*, that forms the floor of the prison, as shown in Figs. 3 and 5.

The vertical bars *a* are actuated by means of a lever, *g*, that is situated in compartment *F*, Figs. 1 and 3, having its fulcrum near the floor, and its lower end entering a mortise in bar *G*, as shown. This lever, when turned toward the dining-hall, draws the bar *G* back, giving the toggle-bar *h* the position shown by the lines, which draws the bar *a* down, so as to allow the projecting ends of the hinges *d* to swing over the catches *e*. The lever by which to actuate the vertical bars that secure the cell-doors is also lettered *g*, and is inclosed in an iron case in the dining-hall, as shown. The case is furnished with a door to afford access to the lever, and a lock to secure it from being tampered with by the prisoners.

The vertical bars *a* are shown in the position to secure the doors; and it will be seen that, when in this position, the toggle-bars *h* stand vertical under them, this being the best position to sustain the weight of bars *a*, and to resist efforts on the part of the prisoners to move them.

When the cells are arranged in stories, as shown in Fig. 5, the doors of the upper story are hung to open in the opposite direction from those below, and the vertical sliding bars that secure those above are coupled by a lever, *R*, to those below, as shown, so that when the lower bars are drawn down the up-

per ones will be raised up, the lugs or catches *e* on the upper bars being reversed to accommodate this motion.

The object of this arrangement is both to provide a convenient and cheap mode of actuating the upper bars and to balance the weight of the lower bars by that of the upper ones, by which the horizontal bar *G* is relieved of the weight, and thus is made easier to operate.

The cell-doors are also spaced the proper distance apart, and hung in such relation to each other that the projections *d* of the hinges will engage with the catches *e* of the bars *a* of the next adjoining cell-door when open in the same manner as when closed, and thus they may be secured open as well as closed, thereby preventing their being injured by the prisoners swinging on them, or otherwise.

The projections of the hinges *d* extend but half across the bar *a*, so that, in case it is desired to leave any of the cell-doors closed, the adjoining cell-door may be secured open by the same bar that secures the closed door. This will be readily understood from the open door drawn in lines in Fig. 5, Sheet 3.

The vertical bars *a* pass through a hole or mortise cut through the stone flagging forming the floor of the prison, and are coupled at their lower ends by the toggle-bars *h* to the horizontal sliding bar *G*, being thus arranged in order to place the joints and working parts of the device that operates the bars out of reach of the prisoners, and where they are not liable to injury by design or accident.

The inner door *D* is furnished with a semi-circular grating, *T*, that projects into the dining-hall, through which to inspect it, for the purpose of observing the movements of the prisoners before entering the hall. This door is secured by a hasp, *H*, attached to a vertical rod, *I*, that is hinged to the door near the top and bottom, and is furnished with hooked projections *O*, that enter holes pierced in the partition *J* when the hasp *H* is turned parallel with the partition, as shown in Figs. 1 and 4.

The hasp *H* is furnished with a staple near its outer end, that passes through a slot cut in the partition *J*, by which the hasp may be secured, by a lock or otherwise, within the compartment *F*. The hasp extends to the outer edge of partition *J*, which is flush with the inner edge of the rabbet into which the exterior doors *B* and *E* shut, and a block or angle-bar, *r*, set a little back from the edge of the door *B* and riveted thereto, projects inward over the end of the hasp, and affords an additional fastening to it when the door is shut.

The door *B* extends, say, one inch on the

edge of partition *J* when closed, and the door *E* of compartment *F* has a flange riveted on its edge, that forms a rabbet that shuts over the edge of door *B*, being the means by which the latter is secured.

The door *E* of compartment *F* may be secured by a system of bolts, such as are employed for similar purposes, as indicated by the lines lettered *v v v v*, Fig. 2. These bolts are to be actuated by means of a crank-lever rigidly fixed in the hinged lever-hasp *L*, and connected with the vertical bar *w*, to which the bolts are attached. The bar *w* may also be furnished with an angular projection, *x*, with which the bolt of lock *Y* may engage, to secure the bolts when thrown out to secure the door *E*. The short end of hasp *L* enters a catch, *L'*, on the door-frame, and the long end is secured on a staple in door *B* by a padlock or otherwise, as may be most convenient.

The partition *J* has an angle-iron bar riveted on its outer edge, on the chamber *F* side, that serves both to strengthen it and to serve as a catch to the ends of the bolts *v v* when thrown out to secure door *E*.

The horizontal bar *G*, under the floor of the prison, may be jointed, as shown in Fig. 3, so that it may turn off at any required angle to accommodate it to the position of the corridor-doors.

One of the notable features of my invention consists in the arrangement of compartment *F* in a position to be inaccessible from the interior of the prison, for the purpose of placing therein the lever *g*, which affords the only means of operating the fastening that secures the corridor-door, and also the fastenings that secure the doors *D*, *B*, and *E*, so as to be out of reach of the prisoners, and at the same time convenient of access by the jailor.

I am aware that devices are in use for avoiding contact with the prisoners, and I make no claim to this feature in prisons, in itself considered; but

What I do claim as new, and desire to secure by Letters Patent, is—

1. The doors *B* and *E*, hinged hasp *L*, bolts *v*, and bar *w*, in combination with compartment *F*, all arranged as and for the purpose set forth.
2. The hasp *H* and hooks *O* for securing the door *D*, in combination with the compartment *F*, arranged as and for the purpose set forth.

BENJAMIN F. HAUGH.
